UNITED STATES PATENT OFFICE.

JOHN S. SHAW, OF DURANGO, COLORADO.

PENCIL-HOLDER.

SPECIFICATION forming part of Letters Patent No. 445,478, dated January 27, 1891.

Application filed May 21, 1890. Serial No. 352,588. (No model.)

To all whom it may concern:

Be it known that I, JOHN S. SHAW, of Durango, in the county of La Plata and State of Colorado, have invented a new and Improved 5 Pencil-Holder, of which the following is a full, clear, and exact description.

My invention is intended to be applied to a slate-frame; and the object of my invention is to provide a convenient receptacle in which 10 a slate-pencil may be securely held and in which the pencil may be easily inserted or removed therefrom.

To this end my invention consists in certain features of construction and combinations of parts, which will be hereinafter fully 15 described and claimed.

Reference is to be had to the accompanying drawings, forming a part of this specification, in which similar letters of reference indicate 20 corresponding parts in all the figures.

Figure 1 is a perspective view of a slate and frame provided with my invention. Fig. 2 is a broken view of the same with the receptacle in open position. Fig. 3 is a broken trans- 25 verse section on the line $x-x$ of Fig. 4. Fig. 4 is a broken detail sectional view showing the receptacle in closed position. Fig. 5 is a detail perspective view of one of the end plates and stops. Fig. 6 is a detail perspective view 30 of the receptacle removed from the slate-frame and having one end attached to the end plate, and Fig. 7 is a cross-section on the line $y-y$ of Fig. 6.

The slate-frame A is of the usual construction, and has a longitudinal groove or recess 35 A' therein, such recess being formed in one of the side rails of the frame, although it may be formed in one of the end rails if desired.

The pencil-holding receptacle B fits closely 40 within the recess A', said receptacle being closed at each end and having at the top a flat plate B', with an opening B² between the lower portion of the receptacle and the plate, said opening being sufficiently large to permit 45 the easy insertion of a pencil into the receptacle. The receptacle B is also provided on the back side with a flange B³, which rests upon a suitable shoulder in the frame A, and the front portion of the plate B' is likewise 50 countersunk into the frame, so that the upper surface of the said plate will be flush with the

upper surface of the said frame, although the receptacle may be sunk deeper into the frame if desired. The frame A has short grooves a 55 therein adjacent to the front edge of the plate B', said grooves thus affording means for grasping the edge of the plate and swinging the receptacle from the frame, as described below.

The receptacle B is provided at each end 60 with suitable springs b, which are fixed to the back thereof by riveting, brazing, or in any suitable manner and which project beyond the ends of the receptacle, so as to engage the plates C and retain the receptacle in the re- 65 cess A' of the frame, with suitable pintles b', which project from each end near the rear portion of the receptacle and are adapted to engage the perforations c of the plates C, thus affording means for pivoting the receptacle 70 in the recess A', and with suitable stops b², which project from each end and which are adapted to engage the horizontal portion C² of the plate C and limit the upward movement 75 of the receptacle. The plates C extend downwardly into the recess A' at each end of the receptacle B, said receptacle being hinged thereto, as shown, and the plates are each provided with a horizontal portion C², which overlaps the frame A on each side of the recess A' and 80 which is firmly secured to the frame.

To insert a pencil in the receptacle, the plate B' of the receptacle is raised, thus swinging the receptacle upwardly and bringing the opening B² therein above the surface of the 85 frame A, so that a pencil may be easily placed within the receptacle. This movement is clearly shown by dotted lines in Fig. 3. When the receptacle is swung upwardly, as described, the ends of the springs b will press firmly 90 against the back edge of the plate C, and when the plate is released the springs b will force the receptacle back into the recess A', thus inclosing the pencil therein. When the receptacle is raised, as described, the stops b² 95 thereon will engage the horizontal portions C² of the plates C and limit the upward movement of the receptacle, so that too much strain will not be placed upon the springs b.

It is obvious that the receptacle B and the 100 recess in the frame A may be made to fit any size or style of pencil.

Having thus described my invention, I claim as new and desire to secure by Letters Patent—

1. The combination, with a slate-frame having a longitudinal recess therein, of a spring-actuated receptacle pivoted in the recess and having an opening in the side to receive a pencil, said receptacle having a flat top portion countersunk in the frame and having projecting stops fixed to each end thereof, and plates fixed in the ends of the recess and adapted to engage the stops of the receptacle and limit the movement thereof, substantially as described.
2. The combination, with the frame A, having a recess A' therein, and the depending plates C, fixed in the ends of the recess and having a downwardly-projecting portion C', as shown, of the receptacle B, pivoted in said plates and provided with a flat portion B' and flange B³, said portions being countersunk in the frame, an opening B³ in the side thereof,

springs b, fixed to the receptacle and adapted to engage the plates C, as shown, and stops b², projecting from the ends of the receptacle 25 and adapted to engage the horizontal portion C² of the plates C and limit the movement of the receptacle, substantially as described.

3. The combination, with the slate-frame having a longitudinal recess therein and the 30 plates fixed in the ends of the recess and provided with depending portions, as shown, of the receptacle pivoted in the plates and fitting the recess of the frame, said receptacle having springs fixed to the back and projecting from the ends to engage the fixed plates, stops projecting from the ends to engage the depending portions of the plates, and an opening in the side to receive a pencil, substantially as described.

JOHN S. SHAW.
